Primary Examiner — Bao-Yen T Nguyen*Assistant Examiner* — Amanda J Berlinski(74) *Attorney, Agent, or Firm* — IPUSA, PLLC(57) **CLAIM**

The ornamental design for a dental syringe, as shown and described.

DESCRIPTION

FIG. 1 is a perspective view of a dental syringe, showing our new design;

FIG. 2 is a front view thereof;

FIG. 3 is a bottom plan view thereof;

FIG. 4 is a right side view thereof;

FIG. 5 is a left side view thereof;

FIG. 6 is a top plan view thereof; and,

FIG. 7 is a bottom plan view thereof.

The de-emphasized light gray areas in the drawings depict portions of the dental syringe that form no part of the claimed design.
